Attorney

UNITED STATES PATENT OFFICE.

AMBROSE A. ZWIEBEL, OF WILKES-BARRE, PENNSYLVANIA.

UMBRELLA.

Application filed February 3, 1927. Serial No. 165,626.

This invention aims to provide novel means for connecting a broken umbrella rib with the notch.

In the drawings:—

5 Figure 1 shows in elevation, a portion of an umbrella equipped with the device forming the subject matter of this application;

Figure 2 is a longitudinal section of the retainer;

10 Figure 3 is a bottom plan of the retainer;

Figure 4 is a longitudinal section showing the retainer and the latch in operative relation to each other and to the notch, prior to the assembly of the parts specified;

15 Figure 5 is a longitudinal section showing the device assembled with the pivot element of the umbrella notch;

Figure 6 is a cross section on the line 6—6 of Figure 5;

20 Figure 7 is a plan of the latch.

The numeral 1 marks the staff of an umbrella, the staff carrying a notch 2 provided with pivot elements 3 whereon the ribs 4 are mounted to swing, the ribs generally being

25 of trough shape in cross section. Suppose that one of the ribs, designated specifically by the numeral 5, is broken off as

30 shown at 6, and that it is desired to renew the pivotal connection between the broken rib 5 and the notch 2. Then, the inner end of the broken rib 5 is placed in a retainer 7, preferably in the form of a trough-shaped

35 socket, the socket or retainer 7 being supplied at its outer end with a longitudinal slot 8 forming arms 9 having transverse

40 fingers 10 which engage and hold the broken rib in the socket 7. The device may be made to operate in two ways, the showing of the drawings being the same in either instance.

45 First, the socket 7 may be made of stiff but bendable material, and, then, the arms 9 and the fingers 10 are pinched about the broken rib 5 with a pair of pliers or any

other suitable tool, or, if preferred, the arms 9 and the fingers 10 may have resiliency 45 enough so that the inner end of the broken rib 5 may be sprung into the socket or retainer 7, without the use of tools.

In its forward end, the retainer 7 has a longitudinal slot 11 located between parallel extensions 12 having hooks 14, the bills of which extend upwardly, as shown in Figure 2. Within the socket or retainer 7 is located a latch 15, in the form of a bar, the latch being retained in place by the 50 fingers 10. The latch 15 is thinned at its inner end, as shown at 18, and is provided with a hook 16, the bill of which extends downwardly, as shown in Figures 4 and 5, the parts 7 and 15, thus, being provided 55 with oppositely facing hooks which cooperate to form a closed bearing receiving the pivot element 3, and constituting a means whereby the broken rib 5 is pivotally assembled again with the notch 2. For convenience in handling the latch 15, it may be provided at its rear end with an off-set bend 17.

60 What is claimed is:—

In a device of the class described, a 70 trough-shaped socket and a retainer bar, the socket and the bar having oppositely facing hooks, the socket being provided with a longitudinal slot through which the hooked end of the retainer bar extends, 75 whereby the socket and the retainer bar may be disposed in crossed relation and closed together, like a pair of pliers, to cause the hooks to cooperate in forming a pivot eye, the socket being provided with 80 means for engaging the retainer bar to hold the retainer bar within the socket.

In testimony that I claim the foregoing as my own, I have hereto affixed my signature.

AMBROSE A. ZWIEBEL.
